UNITED STATES PATENT OFFICE.

LOUIS ALLIS AND ADOLPH R. WIENS, OF MILWAUKEE, WISCONSIN; SAID WIENS
ASSIGNOR TO SAID ALLIS.

FLY-KILLER.

1,055,998.

Specification of Letters Patent. Patented Mar. 18, 1913.

Application filed May 20, 1912. Serial No. 698,417.

To all whom it may concern:

Be it known that we, LOUIS ALLIS and ADOLPH R. WIENS, both citizens of the United States, and residents of Milwaukee, in the county of Milwaukee and State of Wisconsin, have invented certain new and useful Improvements in Fly-Killers; and we do hereby declare that the following is a full, clear, and exact description thereof.

Our invention refers to insect-killers, its object being to provide a simple, economical, effective and compact device of this character, the same comprising a plurality of flat, foldable fan-like strands, in the form of a brush which is provided with a hollow handle that constitutes a shield for the same when the strands or bristles are folded, and when so folded the device assumes a compact form concealing the bristles, in which folded position said device can be conveniently carried about the person for use as conditions may warrant.

At the present time science has demonstrated that many of the infectious diseases are carried by the bite of insects such as flies, mosquitos or the like and so far as we are aware while many forms of insect destroyers have been devised the development of manually operated insect killers has been confined to large, unwieldy household articles, the size of which precludes their use by individuals owing to the fact that such devices are too cumbersome to carry about.

Our device meets all the requirements of the general type but at the same time can be carried in the pocket for any emergency and is designed in such attractive form that it readily appeals to the general public.

In carrying out our invention it is apparent that the generic idea, to wit: a foldable device, can be mechanically accomplished in a variety of ways within the knowledge of those skilled in the art and we therefore do not wish to be confined to any specific structural details. With this in view we have shown two forms of foldable devices, as mechanical examples of conveniently carrying out our invention, one being telescopic and the other foldable upon the jack-knife principle.

With the above object in view our invention consists in certain peculiarities of construction and combination of parts as fully set forth hereinafter with reference to the

accompanying drawings and subsequently claimed.

In the drawings Figure 1 represents a face view of a telescopic form of insect destroyer embodying the features of our invention, the same being shown with the brush or strands in their spread or open position with parts broken away and parts in section to more clearly illustrate certain structural features; Fig. 2, a similar view of the same in its closed position ready to be conveniently dropped into a pocket or other receptacle; Fig. 3, a longitudinal sectional view of the device in its closed position, the section being indicated by line 3-3 of Fig. 2; Fig. 4, an enlarged detail cross-sectional view of our preferred form of strand separating and spreading means, the section being indicated by line 4-4 of Fig. 3; Fig. 5, a cross-section of one form of manipulating slide, the section being indicated by line 5-5 of Fig. 1; Fig. 6, a cross-section of another form of manipulating slide; Fig. 7, a detailed longitudinal sectional view of still another form of manipulating slide showing the same constructed from an offset tongue that is integral with the brush carrying plug, and Fig. 8, a perspective view of the same.

Referring by characters to the drawings 1 represents a hollow handle which is constructed from a single piece of metal pressed in tube form, the longitudinal edges of which tube are spaced apart to form a slot 1' that extends from the point adjacent to the lower end of the handle to a point at a distance from the upper end, which upper end is flattened to constitute a fan-like open mouthed head 2. The edges of the metal at the head are lapped as shown and secured together by a tongue 3, which tongue projects through a slot 4 in the upper lap, the tongue being inserted through the slot and thereafter bent down. The lower end of the handle slot terminates with abrupt shoulders, whereby the edges of the metal are brought together to form a continuous lap over which is inserted a confining ferrule 5, having a tongue 6 which is fitted over the terminal edge of the slot and bent downward to form a keeper for said ferrule. By this construction it is apparent that the hollow handle is entirely confined by the slot and tongue 3, 4, at the upper end and

the interlocked tongued ferrule at the lower end whereby soldering is dispensed with and cheapness in the assemblage is effected.

A slideable hollow plug 7 is fitted into the hollow handle, prior to the blank forming the handle being folded and this plug carries a plurality of flexible strands 8, which strands are preferably formed from wire loops, their free ends being pushed through the end of the ferrule, while their looped ends are soldered thereto and thereafter the ferrule is flattened upon said strands so as to cause the latter to normally lie in a thin sheet. After the strands are thus secured within the plug they are separated into a plurality of fan-like tufts 8' by the insertion of a short coiled section of wire 9, the loops of which wire thus serve as permanent separators and spreaders for the plurality of tufts and owing to the spiral winding of the wire section, when the same is inserted upon the bristles, it will assume a slightly oblique position. The coiled section of wire, constituting the separator and spreader, after being placed in position is, together with the plug and bristles, fitted into the open head of the handle member and thereafter said handle member is folded in shape. When so folded the separator and spreader 9 will be nested into an oblique seat 10, that is formed by channels in the opposite walls of the head 2, said channels being pressed into shape in forming the handle blank.

As shown in Figs. 1 to 5 inclusive, one wall of the plug 7 is cut away to form a strap 7', which strap is brought up through the handle slot 1' for engagement with a slide ring 11 that is loosely fitted about the handle, the said strap being lapped over the slide ring, and thereafter looped about the same as best shown in Fig. 3, whereby the slide ring and plug are permanently engaged. By this connection the operator can readily manipulate the plug which is slid back and forth within the handle incidental to exposing the bristles or folding the same within the head.

From the foregoing description it is apparent that when the plug is pushed toward the head, the spreading separator 9, will cause the tufts to slide between its confining coils and this wedging action will thus open the tufts in a fan-like spread as shown for use. The device can then be manipulated for killing insects and when it is desired to close said device, it is only necessary to draw the plug downward, whereby the free ends of the various tufts will be contracted as they travel down within the hollow handle and will finally be entirely concealed within the head as shown in Fig. 2. It will also be observed that there are no obstructions upon the exterior of the device which would cause the same to be caught in the clothing of the person carrying the same and that owing to

the simple provision for spreading the tufts, friction in the operation of opening and closing is reduced to a minimum.

Fig. 6 illustrates another form of plug manipulating device wherein the plug 7" is provided with an aperture for the reception of a slide ring 11', which slide ring in this instance is formed by a looped band having inturned ends, that abut each other and project through the handle slot into the plug aperture whereby said band and plug are confined.

Fig. 7 illustrates still another form of plug and actuating mechanism therefor, in which the plug manipulating slide ring is dispensed with. In this instance one wall of the plug is stamped out to form a loop 12 that has a central button portion 12' which projects through the slot 1' of the handle whereby said plug can be manipulated, this construction being particularly economical and in all respects as effective as that form of plug wherein a slide ring is attached thereto.

In some instances we may, without departing from the spirit of our invention, utilize the lower part of the handle for an eraser, pencil or penholder or like instrument, it being apparent that the same may, in some instances, be connected directly to the plug and manipulated so as to be exposed when the bristles are concealed and it should also be understood that we may employ any suitable material as a substitute for the wire strands shown and that the handle can also be constructed of various grades of material consistent with the requirements, and furthermore while we have shown and described a coiled wire section as a spreader, that pins, teeth or similar articles may be utilized for separating tufts without departing from the spirit of our invention.

We claim:

1. An insect-killer comprising a hollow slotted handle having a flat head, a slideable plug mounted in the hollow handle, means for actuating the plug extending through the handle slot, a plurality of strands arranged to have a fan-like spread extending from said plug, and separating and spreading means carried by the head engageable with the strands whereby the latter are divided into tufts.

2. An insect-killer comprising a hollow handle having a flattened fan-like head, a slideable plug mounted in the handle, a plurality of strands extending from the plug, their free ends being adapted to spread into fan-like form when the plug is moved in one direction and to contract within the head when the plug is moved in the opposite direction, and means carried by said head for separating the strands into a plurality of tufts.

3. A telescopic insect-killer comprising a

hollow handle having an open head, a slide-
able plug mounted in the handle having a
flattened end, and a plurality of strands ex-
tending from the flattened end of the plug,
5 their free ends being adapted to spread into
fan-like form when the plug is moved in one
direction and to contract within the head
when the plug is moved in the opposite di-
rection.

In testimony that we claim the foregoing 10
we have hereunto set our hands at Milwau-
kee in the county of Milwaukee and State of
Wisconsin in the presence of two witnesses.
